(57) **CLAIM**

The ornamental design for a modular table, as shown and described.

DESCRIPTION

FIG. 1 is a perspective view of a modular table showing the new design;

FIG. 2 is a bottom perspective view thereof;

FIG. 3 is a top view thereof;

FIG. 4 is a bottom view thereof;

FIG. 5 is an end view thereof, the opposing end view being a mirror image thereof; and,

FIG. 6 is a side view thereof, the opposing side view being a mirror image thereof.

The broken line portion of the figure drawings is included to show portions of the article that form no part of the claimed design.

1 Claim, 6 Drawing Sheets(56)
